BOLT AND CHAIN LOCK

Frank R. West, Detroit, Mich.

Application February 26, 1934, Serial No. 712,932

8 Claims. (Cl. 292—264)

This invention relates to a bolt and chain lock, and has to do particularly with the construction of the retainer member for the bolt.

It is the object of the present invention to provide a bolt and chain lock, the retainer member of which is of such construction as to permit the opening of the door to a plurality of independent fixed positions by an extremely simple and easy movement of the bolt itself; at the same time to positively prevent the door from being opened past package receiving position. More specifically, the present invention contemplates a bolt and lock unit wherein the retainer member is somewhat analogous to the standard type bolt and chain lock wherein the retainer member has a straight length of slot, except that here the slot is formed as a tortuous but substantially continuous passageway, the bolt being adapted to remain in any one of a plurality of positions in this tortuous passageway to positively fix the door at that position.

The tortuous passageway is so positioned and the locking points for the bolt thereon so arranged that any attempt to displace the bolt from the outside when the door is in maximum package receiving position will merely result in closing of the door without any possible release of the bolt. In the preferred embodiment the next to the last point on the tortuous passageway positions the door at crack position (about $\frac{1}{8}$ " opening); the last position being really two alternative positions, one in a downward direction for locking the door in closed position and the other in the other direction for releasing the bolt from the retainer member.

Other features of the invention, including particularly the detailed construction of the retainer member, will be more clearly set forth in the specification and claims.

40 In the drawing:

Fig. 1 is a fragmentary elevational view of a door and casing equipped with a bolt and chain lock embodying the present invention.

Fig. 2 is a sectional plan view taken on line 45 2—2 of Fig. 1, showing the door and chain locking device in a plurality of positions of adjustment in both full and dotted lines.

Fig. 3 is a sectional view taken on line 3—3 of Fig. 1.

50 The present invention preferably embodies a standard keeper member 2 adapted to be secured to a door casing 3, a chain 4 terminating in a locking bolt 5 adapted to cooperate with a retainer member 6. The gist of the present invention resides in the construction of this retainer

member 6, which in the illustrated embodiment is secured to the door by means of suitable fastening screws 7.

As best shown in Figs. 2 and 3, the retainer member comprises a base portion 8, side walls 9 and a top plate 10, provided with what might be termed a tortuous slot 11. The locking bolt 5 is provided with a head 12 adapted to fit within an enlarged opening 13 at the end of the slot 11, a groove portion 14 permitting the bolt to be slid along the slot or groove 11 in the top plate 10 of the retainer.

When the retainer member 6 is mounted in a substantially horizontal position on the door, as shown in Fig. 1, or on the casing, in the event of a reversal of parts, I preferably fabricate the wall portions 15, 16, 17 and 18 of the tortuous slot so as to slightly slope inwardly and downwardly towards the keeper member 2. These wall portions 15, 16, 17, and 18 provide fixed but temporary locations for the bolt 5 and hence for the door. The slightly inclined walls will tend to retain the bolt in any one of the temporary but fixed positions in case of any attempt by jarring or otherwise to move the bolt from the outside, say, from the position 17 to the position 15. The general contour of the groove 11 is maintained however so that it is a very easy matter to move the bolt along the groove.

The position 18 is the fixed but temporary position of the bolt as a night lock, that is, when the door is completely closed. From this position it is very easy to move the bolt up to the aperture 13 where it can be removed to permit immediate opening of the door if desired.

The wall 17 forms the second position which is what we term the observation position for the lock and for the door. As illustrated in dotted lines in Fig. 2, this position of the door is illustrated at 17a, and when the bolt is in this position 17 the door may be opened just wide enough to peer through and see who is on the outside. If it is desired to receive a newspaper or other fairly small article, the bolt may be then removed along the tortuous passageway to the position 16, which is the position of the door shown at 16a in Fig. 2, with the result that the door may be then opened wide enough to receive the newspaper or other small package.

The last position of the locking member and of the door as illustrated in the embodiment is that illustrated by the position 15 in Fig. 1 and the solid line position of the door and the locking member as shown in Fig. 2. Here the door is in

its maximum open position permitted by the length of the chain.

It will be obvious that the offset portions of the slot may vary considerably in their arrangements, 5 degree of slope, etc., but the main point is that a plurality of positions other than the night lock position are provided at which the locking bolt will be temporarily fixed so as to securely hold the door at the position determined by the particular 10 depression or wall against which the bolt is held by gravity. It will be understood that the enlarged opening 13 may be positioned at various points, but I preferably arrange the same adjacent the night lock position 18 or the cracking 15 position of the door 17 because it is from these two positions that the bolt is most frequently removed from the retainer.

It will thus be seen that I have provided a 20 retainer member of very simple cheap construction and which provides for absolute safety as far as the relationship between the bolt and container is concerned. Any attempt by one on the outside to push the bolt towards removable position will be met by a squeezing of the wrist as the bolt is moved towards the position 17. Rubber bands, 25 string, or other means would also fail to move this bolt along the tortuous passageway. A scuff plate 19 may be provided to prevent the chain 4 from marring the edge of the door.

30 The top 10 of the retainer member 6 being flat may be reversed and used with either a right hand or left hand door.

What I claim is:

35 1. A safety lock of the bolt and chain type for securing a door in a plurality of partially open positions, comprising a part for attachment to a door casing including a flexible connection and a lock member, a retainer member adapted to be used on a right hand or left hand door, secured 40 to the door and having a substantially continuous tortuous slot for receiving said locking member, the median line through said tortuous slot being substantially horizontal, said slot having a plurality of surfaces against which the lock member 45 is adapted to automatically contact by gravity and temporarily but fixedly abut to hold the door in a plurality of partially opened positions, the end of said slot branching off in one direction and being so shaped as to hold the lock and door 50 in closed position.

55 2. A safety lock of the bolt and chain type for securing a door in a plurality of partially open positions, comprising a part for attachment to a door casing including a flexible connection and a lock member, a retainer member, adapted to be used on a right hand or left hand door, secured to the door and having a substantially continuous slot for receiving said locking member, said slot 60 having a plurality of surfaces each forming an obtuse angle relative to the inner edge of the door against which the lock member is adapted to temporarily but fixedly abut to hold the door in a plurality of partially opened positions, the end 65 of said slot branching off in one direction and being so shaped as to hold the lock and door in closed position, and in another direction where it merges into an enlarged opening for removing the lock when the door is in substantially closed 70 position.

75 3. A retainer member for bolt and chain door locks comprising a casing having an opening for receiving a chain locking member, said casing being adapted to be permanently mounted, and a slot in the face of said casing for receiving and

guiding the locking member in the same plane, said slot having a plurality of surfaces each forming an obtuse angle relative to the inner edge of the door against which said lock member is adapted to temporarily but fixedly abut to hold the door in a plurality of positions, said slot being substantially unbroken from one extreme positioning surface to the other.

4. A retainer member for bolt and chain type locks for doors, comprising a casing adapted to be 10 permanently mounted, a slot substantially continuous formed in said casing for receiving a chain locking member, said slot extending generally lengthwise of the casing, portions of said slot being offset to form a plurality of spaced positioning surfaces each forming an obtuse angle 15 relative to the inner edge of the door against which said member is adapted to automatically and fixedly but temporarily abut.

5. A retainer member for bolt and chain type 20 locks for doors, comprising a casing adapted to be permanently mounted, a substantially continuous slot formed in said casing for receiving a chain locking member and guiding the same in the same plane, said slot extending generally 25 lengthwise of the casing, portions of said slot being offset to form a plurality of spaced positioning surfaces against which said member is adapted to automatically and fixedly but temporarily abut, the face of said casing being substantially 30 parallel to the plane of the door when the door is closed.

6. A retainer member for bolt and chain type locks for doors, comprising a casing adapted to be 35 permanently mounted, a flat plate adapted to contact with the face of said casing, a continuous slot formed in said plate, said slot having an enlarged opening in one end to receive an enlarged head of a chain locking member and being narrow for the rest of its length whereby 40 said head slides in the space between the flat plate and the casing, said slot and enlarged opening being so formed that the plate may be reversed and used either as a right or left hand plate, said slot having a smooth sinuous formation 45 the median line of which extends longitudinally of the retaining member, at least one transverse portion of the sinuous formation being positioned intermediate the ends of the slot and against which the locking member is adapted 50 to automatically contact by gravity to temporarily but fixedly hold the door in a position intermediate its open and closed positions as determined by the respective ends of the slot.

7. A safety lock of the bolt and chain type for 55 securing a door in a plurality of partially open positions, comprising a part for attachment to a door casing including a flexible connection and a lock member, a retainer member secured to the door and having a substantially continuous tortuous slot for receiving said locking member, and guiding the same in the same plane, the median line through said tortuous slot extending longitudinally of the retaining member, said slot having a plurality of surfaces against which the 60 lock member is adapted to temporarily but fixedly abut to hold the door in a plurality of partially open positions.

8. A safety lock of the bolt and chain type for 65 securing a door in a plurality of partially open 70 positions, comprising a part for attachment to a door casing including a flexible connection and a lock member, a retainer member secured to the door and having a substantially continuous slot for receiving said lock member and guiding the 75

same in the same plane, the median line through said tortuous slot extending longitudinally of the retaining member, said slot extending generally transversely of the door and having a plurality 5 of surfaces against which the lock member is adapted to temporarily but fixedly abut to hold the door in a plurality of partially opened pos-

tions, the end of said slot branching off in one direction and being so shaped as to hold the lock and door in closed position, and in another direction where it merges into an enlarged opening for removing the lock when the door is in 5 substantially closed position.
